RADIATOR CONSTRUCTION
George Gerard, 1698 East Drive, West Point
Pleasant, N.J.

Filed Oct. 14, 1959, Ser. No. 846,369
6 Claims. (Cl. 257—136)

The present invention relates to a radiator construction and it particularly relates to a radiator construction for hot liquid systems.

It is among the objects of the present invention to provide a simple, compact radiator system particularly designed for achieving maximum heat utilization with circulating hot liquids systems.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects it has been found most satisfactory, according to one embodiment of the present invention, to provide a fin construction in which the pipes extending through a series of parallel, closely spaced fins will be so arranged as to be conveniently located in recesses within the wall of a room or along the side of the wall without undue or uneconomical space consumption.

It has been found, according to the present invention, that, with one header outlet and return, connections may be readily made with assurance of maximum utilization and circulation of the hot liquid in its passage from the furnace and back to the furnace.

Desirably a series of parallel horizontal pipes are positioned in a wall recess which may be insulated from the rear so that full heat reflection will occur forwardly into the room space.

The units consisting of a plurality of fins, the spaces between which are closed by in-turned flanges, may be positioned with their front edges in or along the plane of the wall.

The inlet and outlet connection to each radiator series is achieved by having pipes in the main header facing the direction of flow and away from the direction of flow so as to create a forced flow through the radiator sections themselves.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

FIG. 1 is a side diagrammatic elevational view illustrating the connection between the radiators and the main headers.

FIG. 2 is a transverse sectional view indicating how the radiator unit may be inserted in the wall of a room or other enclosure.

Referring to FIG. 1, there is shown the main flow pipe

2

A carrying the heated liquid which may be of light or medium bodied oil, with the branch connections B as an inlet and C as an outlet to the various radiator sections C, D E and F which are inserted in the wall structure G.

5 Each radiator section C, D, E and F has a horizontal main pipe or tube H with a plurality of radiating fins J and with the inlet connection K and the outlet connection L respectively.

The units are held in position by means of the spring 10 clips or resilient members M which extend inwardly from the wall sections N. The radiator unit has a back casing P and a front closure frame Q.

Referring to the main flow pipe A, which may be positioned between the walls or between the ceiling and floor, 15 the hot oil is caused to flow in the direction 10 under pump pressure from a furnace.

At the inlet connection B the end of the tube, as indicated at 11, faces the direction of the oil flow and has a slight enlarged bell-shaped mouth 12, with the 20 result that oil will be forced at 13 into the curved inlet neck B.

At the other side there will be an end portion 14 extending in the direction of flow and the hot liquid will be drawn out, as indicated at 15, through the curved outlet 25 neck section C. Both units B and C are joined into the pipe A by the strong connections 16 and 17.

The piping B connects to the end header K, which extends through the end portions 18 of the horizontal tubes H.

30 There are flow connections as indicated at 19 adjacent the top of the pipe H. Similar connections are provided at the outlet side L, which also extends through the ends 20 of the headers H. Here, too, the openings 21 are positioned at the top.

35 The fins J, which may be closely spaced and parallel to each other, are mounted upon each tube H and may be soldered thereto at their central portions. The spring clips M, which are bolted, riveted or screwed at 22 at their lower ends 23, have upper bifurcated sections 24 which fit on to and hold the pipe sections H in position.

Each tube H may be provided with the locator members N at the ends thereof. As shown in FIG. 2, there are four horizontal tubing sections, each having upper circular openings eccentrically disposed, as indicated at 19 in FIG. 2.

40 The fins J are spaced apart by the spaces 35, and, if desired, their front ends may be flanged in one direction so as to close the spaces 36 between them and give maximum radiating surface.

45 The open portions, as indicated at 37 and 38, permit the air to pass in, as indicated at 39, and pass out, as indicated at 40, to give maximum radiating effect.

The frame Q may carry an ornamental grill and the 50 back plate or casing P may be made of sheet steel or of other metal material, preferably with an interiorly polished face, as indicated at 41.

Desirably the fin length will terminate inside of the headers K and L, with the ends of the pipe projecting 55 adjacent to but not touching the wall sections N so as to leave space for expansion.

60 The entire unit is very compact and the varying number of sections may be employed from one horizontal pipe H to four or more horizontal pipes H.

The fins should extend the full width of the recess, as indicated at P in the wall, and they may be made of square or aluminum sheet spaced one inch apart and 2½ inches square.

The piping H may be copper piping 7/8 outside diameter, with 1/32 wall thickness and the openings 19 may be 5/16" in one preferred construction.

The upper ends of the vertical members K and L are plugged, as also are the ends of the horizontal tubes H.

The inlet and outlet connections, as indicated at B and 10 C, will give a Venturi tube effect and will assure a forced flow of hot oil or other liquid through the radiators consisting of the horizontal pipes H and the fins J.

The system will be most effective in heat utilization and may be conveniently installed, particularly with hot 15 oil systems.

As many changes could be made in the above radiator construction, and many widely different embodiments of this invention could be made without departure from the scope of the claims, it is intended that all matter contained in the above description shall be interpreted as 20 illustrative and not in a limiting sense.

Having now particularly described and ascertained the nature of the invention, and in what manner the same is to be performed, what is claimed is:

1. A radiator system of the type having a rectangular recess in a wall with a cover for the recess flush with the wall and air flow openings at the top and bottom of the cover having a main hot liquid feed pipe with inlet and outlet connections and a plurality of horizontal pipe members carrying closely spaced rectangular fin members with tubular vertical end headers connected to said inlet and outlet connections, said inlet connection facing upstream and said outlet connection facing downstream in said hot liquid feed pipe, said fin members for each horizontal pipe member extending from the back of the recess to the cover of the recess and the upper and lower ends of the fin members terminating just short of the fin members on the next adjacent horizontal pipe member and said horizontal pipe members being larger in diameter than the vertical headers and extending beyond the vertical headers to adjacent the end walls of the recess and said vertical headers extending through the ends of the horizontal pipe members with their vertical and horizontal axes intersecting at the center of the horizontal pipe members and the vertical headers.

2. A radiator system of the type having a rectangular recess in a wall with a cover for the recess flush with the wall and air flow openings at the top and bottom of the cover having a main hot liquid feed pipe with inlet and outlet connections and a plurality of horizontal pipe members carrying closely spaced rectangular fin members with tubular vertical end headers connected to said inlet and outlet connections, said inlet connection facing upstream and said outlet connection facing downstream in said hot liquid feed pipe, said pipe members with said fin members being recessed into the wall and resilient clips holding said pipe members in position, said fin members for each horizontal pipe member extending from the back of the recess to the cover of the recess and the upper and lower ends of the fin members terminating just short of the fin members on the next adjacent horizontal pipe member and said horizontal pipe members being larger in diameter than the vertical headers and extending beyond the vertical headers to adjacent the end walls of the recess and said vertical headers extending through the ends of the horizontal pipe members with their vertical and horizontal axes intersecting at the center of the horizontal pipe members and the vertical headers.

3. A radiator system of the type having a rectangular recess in a wall with a cover for the recess flush with the wall and air flow openings at the top and bottom of the cover having a main hot liquid feed pipe with inlet and outlet connections and a plurality of horizontal pipe members carrying closely spaced rectangular fin members

with tubular vertical end headers connected to said inlet and outlet connections, said inlet connection facing upstream and said outlet connection facing downstream in said hot liquid feed pipe, said inlet and outlet connection consisting of quarter circular tubes inserted into the main feed pipe, with the inlet tubes having a belled mouth facing upstream and the outlet connection extending downwardly in the middle of the downstream side of the feed pipe, said fin members for each horizontal pipe member extending from the back of the recess to the cover of the recess and the upper and lower ends of the fin members terminating just short of the fin members on the next adjacent horizontal pipe member and said horizontal pipe members being larger in diameter than the vertical headers and extending beyond the vertical headers to adjacent the end walls of the recess and said vertical headers extending through the ends of the horizontal pipe members with their vertical and horizontal axes intersecting at the center of the horizontal pipe members and the vertical headers.

4. A radiator system of the type having a rectangular recess in a wall with a cover for the recess flush with the wall and air flow openings at the top and bottom of the cover having a main hot liquid feed pipe with inlet and outlet connections and a plurality of horizontal pipe members carrying closely spaced rectangular fin members with tubular vertical end headers connected to said inlet and outlet connections, said inlet connection facing upstream and said outlet connection facing downstream in said hot liquid feed pipe, said vertical end headers extending upwardly through the ends of said horizontal pipe members and having open connections to said horizontal pipe members at the upper sides of the pipe members, said fin members for each horizontal pipe member extending from the back of the recess to the cover of the recess and the upper and lower ends of the fin members terminating just short of the fin members on the next adjacent horizontal pipe member and said horizontal pipe members being larger in diameter than the vertical headers and extending beyond the vertical headers to adjacent the end walls of the recess and said vertical headers extending through the ends of the horizontal pipe members with their vertical and horizontal axes intersecting at the center of the horizontal pipe members and the vertical headers.

5. A recessed wall radiator construction comprising of the type having a rectangular recess in the wall with a cover for the recess flush with the wall having bottom and top openings for inflow and outflow of air to be heated and after being heated respectively, said recess having semi-cylindrical top and bottom inside wall surfaces to direct the incoming cool and outgoing heated air, said radiator construction having vertical spaced side tubular inlet and outlet pipe members positioned closely adjacent to the sides of the recess and transverse horizontal pipes of larger diameter than the vertical pipe members extending between and beyond the vertical pipe members and said vertical pipe members extending centrally through the ends of the transverse pipe members and having off center openings into the ends of the transverse pipes substantially above the center lines of the transverse pipes and between the upper portion of the vertical pipe members where they extend through the horizontal pipe members, each horizontal pipe having a plurality of closely spaced transverse rectangular fins independent of the fins on the next upper and lower transverse pipe and spaced at their upper and lower edges from those on the next adjacent transverse pipes and said fins extending from the back to the front of the recess below and above said semi-cylindrical wall surfaces and a main horizontal supply tubular conduit for heating fluid positioned below said recess and said vertical pipe members having right angular 90° turns extending into the center of said tubular conduit with the end of the inlet vertical pipe member facing upstream and the end of the vertical

outlet pipe member facing downstream, said tubular conduit having an enlarged diameter so as to form an annular passageway around the 90° turned lower ends of the vertical pipe members.

6. The construction of claim 5, the walls of said recess having spring clipped means positioned against the ends of a horizontal pipe and the outside faces of the vertical pipe members to hold the radiator construction centrally positioned into the rectangular recess and the inlet end of the 90° turned lower end of the inlet vertical pipe section having an enlarged conical mouth so that it will have

5

a larger area facing the direction of flow than the area of the 90° turned lower end of the outlet vertical pipe section.
